UNITED STATES PATENT OFFICE.

JOSEPH E. CAMP, OF WASHINGTON, ILLINOIS.

PORTABLE ELEVATOR.

No. 825,109.

Specification of Letters Patent.

Patented July 3, 1906.

Application filed March 3, 1905. Serial No. 248,353.

To all whom it may concern:

Be it known that I, JOSEPH E. CAMP, a citizen of the United States, residing at Washington, in the county of Tazewell and State 5 of Illinois, have invented certain new and useful Improvements in Portable Elevators; and I do hereby declare that the following is a full, clear, and exact description of the invention, which will enable others skilled in 10 the art to which it appertains to make and use the same.

This invention has reference to portable elevators of that class employed for handling grain.

15 The primary object of my present invention is to provide an elevator and its short conveyer or "drag" with a single elevating-chain.

20 A further object is to provide a mechanism in a portable elevator by which the driving power is applied directly at the top of the elevator or head.

25 Another object is to provide a conveyer or drag for an elevator so arranged that the latter may be raised or lowered while the drag remains in a horizontal position.

30 Another object is to so arrange an elevator and drag that the former can be partially folded back upon itself and the latter raised out of the way for transportation purposes.

35 In addition to the above my invention relates to certain new and novel details of construction, as will be pointed out in the following specification and embodied in the appended claims, aided by the drawings, in which—

Figure 1 is a side elevation of my complete portable elevator and drag. Fig. 2 is a top view of the same. Fig. 3 is a side elevation 40 of a portion of the elevator and drag, showing parts in section. Fig. 4 is a perspective view of a chain tightening and loosening means. Fig. 5 is a detail of a portion of Fig. 4. Fig. 6 is a perspective view of a drag member, showing its position between two chains. Fig. 7 is an end view of the elevator with its drag removed. Fig. 8 is a perspective view of one-half of a shaft connection. Fig. 9 is a similar view of the other half of the 45 shaft connection. Fig. 10 is a perspective view of a covered sprocket-wheel beneath which one of the elevating-chains runs. Fig. 11 is a cross-sectional view of a shaft and bottom of the drag, showing a plate carried 50 on the former and resting upon the latter. A indicates a triangular carrying-frame

mounted upon wheels B at front and rear, as shown, the front ones being arranged so as to turn by means of a fifth-wheel, which, however, is not shown, a tongue C being provided for that purpose. At the forward end of the frame A is pivotally carried, by means of brackets D D, one end of the elevator (represented at E.) The opposite end of the elevator has the usual head F, which is separate 60 from the main elevator portion, being hinged to the latter at the top by means of the hinge members G, so that it can be folded back, as shown in broken lines in Fig. 1. The bottom of the elevator is shown at H in the several figures, the upper end of which terminates within the head F adjacent to a shaft J, which carries two sprocket-wheels K, over which run the chains L L of the elevator and conveyer, (shown at M.) The said shaft J carries at one end, outside the elevator-head, a beveled gear-wheel N, with which engages a similar wheel O, carried on a shaft P, journaled on the side of the elevator by means of the boxings Q. At the lower end of the elevator, at the pivot-point thereof, is a beveled gear R, and with this a wheel S meshes, the shaft T on which it is carried being in line with the shaft P described. Said shaft T is carried in the boxings U, as shown. The adjacent ends of the two shafts P and T are provided with couplings V and W, the former being secured to the shaft P and the latter to shaft T. These members are constructed so that one shall seat within the other to form 70 a tight connection capable of separation at will. In Figs. 8 and 9 these are clearly illustrated, the member V having a series of notches, while the member W is provided with projections to seat therein. Said members are adapted to connect with each other at the place of separation of the elevator and its head, as shown, and it will be seen that when the head is raised on its hinges the members V and W will separate readily, but 75 will come together when the head is returned to its operative position.

Erected upon the carrying-frame A is a derrick 2 in the form of an A, adapted to raise and lower, this being supported in its raised 80 position by means of two arms 3, whose lower ends hook into the members 34 on the said frame A. Carried on the derrick 2 is a shaft 4 and its windlass 5, a crank 6 on the shaft serving to revolve the windlass to raise or 85 lower the elevator, a cable 7 on the said windlass passing up through a pulley 8, hung from 90

the derrick, and thence down to the elevator at the eye 9, where by means of a hook 10 the cable supports said elevator. A ratchet-wheel 11 and pawl 12 serve to sustain the elevator in any position placed, as will be understood. The conveyer or drag M, before mentioned, is pivotally carried at its inner end on the elevator, there being arms 13, secured thereto, as shown at 14, the opposite ends of the arms being pivoted to the elevator in line with the shaft of the gear R, before described. So mounted the conveyer may be raised or lowered at will. At the opposite or outer end of the conveyer is a pivoted yoke or bail 15 for supporting said conveyer when in its horizontal position. The bottom of the latter is shown at 16, and at its extreme outer end is a shaft 17, carrying sprocket-wheels 18, corresponding with the sprockets K at the head of the elevator. Inside the latter, near its lower end, are two sprocket-wheels 19 in line with the sprockets K and 18 and whose lower peripheries are slightly above the bottom H. It will now be seen that, as shown in Fig. 3, the chains L L are designed to traverse the entire length of the elevator and conveyer, and it will be further seen that without some means, such as the sprockets 19, the chains L L would seek a straight line from the wheels 18 to the wheels K. The said wheels 19 therefore hold the chains down near the bottom, so that the drag members 20, one of which is shown in Fig. 6, will travel close to said bottom for properly elevating the grain. These said wheels 19 are suitably journaled close to the inside surfaces of the elevator sides, and each is covered, as shown in Figs. 3 and 10, by a sheet-metal housing 21, letting the bottom edges of the wheels project, however, so that the chains can engage therewith. The drag members 20 are so formed that the chains to which they are secured can pass beneath the wheels 19, said members also passing easily between the housings 21. As a matter of fact the wheels 19 and their housings 21 do not occupy as much room as shown in the drawings, so that the capacity of the elevator is not reduced to any great extent. I preferably place beneath the elevator a pair of wheels 22, beneath which the chains can run, as shown. In use power is applied to the shaft of the gear R from any desired source, from whence it is transmitted, through the gear S and shafts T and P and gear O, to the sprockets K K by means of the gear N. The real power is therefore applied to the head of the elevator, the chains being drawn up with the load of grain. The shaft 17 of the conveyer is carried at each end in a shiftable block 23, only one of which is shown, Fig. 4, said blocks being carried in frames 24, secured to the sides of the conveyer in suitable manner. Each frame has a projection 25, on which are lugs 26, through which passes a plunger 27, surrounded by a spiral spring 28, said spring ex-

erting pressure between one of the lugs 26 and a fixed collar 29 on the plunger. To one end of the plunger is pivoted an arm 30, and an arm 31 is also loosely secured to the block 23, and the free ends of the arms 30 and 31 are connected to form a toggle between the plunger 27 and the block 23. It will be observed that when the toggle is pulled outward the block 23 will be drawn toward the plunger, the latter being limited in its movement, due to the fixed collar 29 behind the lug 26, and it must be understood that a like movement of both the toggles—i. e., one at each side of the conveyer—will operate to shift the shaft 17 in the direction mentioned, with the result that the chains L L are slackened. Now if the toggles are pushed in toward the sides of the conveyer the shaft will be shifted outward to tighten the chains. The sides of the conveyer are slotted to allow the shaft to shift freely. 85

Fig. 11 shows how the gap between the end of the conveyer-bottom 16 and the shaft 17 is kept covered. This is done by bending one end of a piece of sheet metal 32 around the said shaft in a loose manner, as shown, while the straight portion thereof covers the gap and rests upon the said bottom. The chains L L will pass freely over this, and the gap is always covered in any adjustment of the parts. 95

The spring 28 of the plunger 27 is of great strength and is employed to keep a yielding tension on the chains when in operation, so that any undue strain on the chains, due to any cause, will not bind the machine or break any of the parts. 100

The purpose of slackening the chains is that the head of the elevator may be folded back when storing or shipping the machine and also that the conveyer may be raised to the dotted-line position shown in Fig. 3. Much slack is needed for these purposes, as will be seen, and it may be had by the means employed. 105

In operation it may be found expedient to raise the conveyer to let a wagon pass and then let it down behind the wagon ready to receive the load of grain therefrom. In order to do this, it is only necessary to pull the toggles outward, as hereinbefore described, to slacken the chains, raise the conveyer, and afterward let it down and replace the toggles. 110

It is to be noted that the arms 13 are quite long, so that in raising the conveyer they will pass the ends of the elevator. The sides of the former are cut out, as in Fig. 3, so that the housings 21 of the sprockets 19 will not be interfered with in raising on the arms 13. 120

The conveyer is preferably made of sheet metal, so as to have the sides sufficiently thin to pass between the chains and the sides of the elevator, as will be understood. 125

Various changes may be made in my device such as will improve the general con- 130

struction and arrangement without departing from the spirit and intent of the invention, as I do not wish to confine myself to the exact structure shown and described. The 5 arms 3 of the derrick before mentioned are each provided with a hinge 33, by which the said rods can be folded, but when in the position shown in Fig. 1 will sustain any weight placed upon them without voluntarily 10 unlocking. The members 34 on the frame A are adjustable along said frame by means of the wing-nut 35 and its bolt within the slot 36 of the frame, there being sufficient play in the parts to permit the said members 34 sepa- 15 rating or coming toward one another as they follow the slots. By the means thus provided it will be seen that the arms 3 can be adjusted for a fixed height of the elevator and that when they are raised the said ele- 20 vator will always be in the desired position for work at a particular receptacle.

I claim—

1. In a device of the character described, an elevator, wheels therein at the top and bottom, an endless conveyer member carried by the wheels, means outside the elevator and in connection with both the wheels top and bottom of said elevator and driving connection at the lower end of such means for driving it to impart movement to the endless conveyer member from the top of the said elevator.

2. In a device of the class described, an elevator, an endless conveyer member thereing, wheels for carrying and guiding said conveyer member, a shaft carried at the side of the elevator, a gear-wheel at its upper end for connection with the carrying-wheels of the conveyer member, and a power-driven wheel at the lower end of the elevator for driving the lower end of the shaft all for the purposes described.

3. In a device of the class described, a pivoted tiltable elevator, an endless conveyer member therefor, carrying-wheels at the top and bottom of such elevator, a gear-wheel for driving the upper ones, a power-driven shaft journaled on the side of the elevator substantially parallel therewith and substantially parallel with the top and bottom edges thereof and moving with the elevator when raised or lowered, a gear-wheel at the upper end of the shaft for engaging the gear-wheel of the conveyer member, a power-driven gear at the foot of the elevator and a gear-wheel on the lower end of the shaft for engaging the power-wheel of the elevator, the driving power being transferred to the wheels at the top of the elevator through said shaft.

4. In a device of the class described, an elevator, a conveyer pivoted thereto and adapted to discharge grain thereinto, an endless conveyer member within the elevator and conveyer, carrying-wheels in the elevator

and conveyer for the conveyer member, a shaft journaled on the side of the elevator, connections between its upper end and the upper carrying-wheels of the said conveyer member, a power-wheel on the lower end of the elevator and connection between it and the shaft for driving the said shaft and conveyer member at the top for the purposes described.

5. In a device of the class described, an elevator consisting of hinged foldable sections, an endless conveyer member therein, wheels for the same, driving means outside the elevator at the side thereof in connection with the upper carrying-wheels of the conveyer member; and power on the lower end of the conveyer with which the driving means is connected, said driving means adapted for permitting the elevator to fold but capable of driving the conveyer member when the elevator is again opened to its normal working position.

6. In a device of the character described, an elevator of plural sections hinged together and foldable upon one another, a conveyer member therein, wheels for the same, a shaft-section journaled on the outside of and parallel with each of the elevator-sections, the same adapted to interlock when the elevator-sections are operatively connected, the upper shaft-section adapted for driving the top wheels of the conveyer member, and power means for driving the lower shaft-section.

7. The combination, in a portable elevator, of a wheeled support, an elevator pivoted thereto and adapted to raise and lower, means for raising and lowering it, a conveyer-section having pivotal connection with the elevator at the lower end of the latter, said conveyer adapted to tilt on end into the elevator, the latter member having a folding head substantially as shown, wheels in the head of the elevator, companion wheels in the outer free end of the conveyer, elevating means carried by both series of wheels, the same adapted to run through the elevator and conveyer, a shaft carried at the side of the elevator, means for imparting motion thereto, said shaft ending at the joint of the elevator and its head, a second shorter shaft on the head of the elevator, connections between the two shafts, and means at the free end of the shorter shaft for driving the wheels within the elevator-head for imparting motion to the said elevating means substantially as set forth.

8. An elevator, an endless conveyer member and its carrying-wheels therein, a shaft journaled on the side of the elevator and having driving connection with the upper wheels of the conveyer member, a power-wheel carried at the foot of the elevator, the said shaft having connection therewith for driving the said upper wheels of the elevator, the ele-

- 4
- vator having a foldable section, the shaft adapted for separation at the joint of the folding section but capable of rigid connection when in operative position.
- 5 9. An elevator having a conveyer member and carrying-wheels therefor, said elevator having a foldable section hinged to the elevator on the upper side, as shown, the elevator and its section separating at the under side when the latter is turned back on its hinge, a shaft carried on the side of the elevator and comprising two sections jointed at the point of separation of the elevator and its section and capable of driving connection and disconnection at will when the upper elevator-section is swung, to its closed or open position respectively, and a power-wheel at the foot of the elevator having connection with the lower end of the shaft substantially 10 as and for the purposes described.
- 15 10. In a device of the class described, grain-elevating means, an endless conveyer member therein, wheels for carrying the latter and means for slackening the said conveyer member comprising slidable members carrying a set of wheels at one end of the conveyer member, toggle-arms pivoted to each of the slidable blocks and yielding means with which said arms are connected for the purposes described.
- 20 11. In a device of the class described, an elevator, a conveyer therefor in line therewith, a single endless conveyer member extending through both members, wheels for the latter at the head of the elevator and at the outer extremity of the conveyer, a slidable block at each side of the conveyer for carrying and adjusting the wheels therein situated, a toggle-arm pivoted to each slidable block, a second toggle-arm pivoted to the free end of the first, and a spring-held plunger to which the free end of the second arm is pivoted, the said arms, when adjusted in line with one another holding the wheels 25 out to their limit of movement to tighten the 45 chains, springs for keeping a yielding tension on the chain when the arms are in line, the arms when thrown out of line permitting the chains to slacken as set forth.
- 30 12. In a portable elevator, a wheeled frame, an elevator pivoted at one end thereon, a derrick pivoted on the frame, devices carried on the derrick for attachment with and raising and lowering the elevator, and jointed brace-arms for supporting said derrick, said arms 50 being pivoted at one end on the frame and attached to the derrick at the other and adapted to collapse at the joints thereof for the purposes described, said arm being adapted to support the elevator when raised 55 and straightened as shown.
- 35 13. In a portable elevator, a wheeled frame, an elevator pivoted on said frame, devices thereon for connecting with and raising and lowering the elevator and arms pivoted at 60 their lower ends to the frame and having connection with the derrick at the other, and a hinged joint for each arm, the pivot of each joint lying outside of the line of thrust of the weight on the arms when the said arms are 65 in their position for supporting the elevator.
- 40 14. In a portable elevator, a wheeled frame, an elevator pivoted thereon, a conveyer pivoted at one end to and within the elevator substantially as described, a derrick pivotally 70 mounted on the frame, devices thereon connected with the elevator for raising and lowering said elevator, and jointed brace-arms pivoted to the frame and having connection with the derrick and adapted to collapse at 75 the joints for the purposes described.
- In testimony whereof I affix my signature in presence of two witnesses.
